COMBINED CLOTHES DRIER AND CANOPY

Harry M. Lewis, Los Angeles, Calif.

Application June 18, 1945, Serial No. 600,085

1 Claim. (Cl. 211—178)

1

My invention relates to a combined clothes drier and canopy and has for its principal object, to combine with a collapsible outdoor clothes drying frame or rack, a cover canopy, preferably of fabric and further, to provide simple, and easily operated means for drawing the canopy into a compacted body above the supporting post of the structure when the same is in use as a clothes drier and to draw said cover over the entire top of the frame, thus providing, in effect, a lawn umbrella or canopy of considerable size.

With the foregoing and other objects in view, my invention consists in certain novel features of construction and arrangement of parts, which will be hereinafter more fully described and claimed and illustrated in the accompanying drawings, in which:

Fig. 1 is a plan view of my improved clothes drier and canopy with parts broken away.

Fig. 2 is a vertical longitudinal section taken approximately on the line 2—2, of Fig. 1.

Fig. 3 is an enlarged detail section on the line 3—3, of Fig. 2.

Fig. 4 is an enlarged detail section taken on the line 4—4, of Fig. 1.

Figs. 5 and 6 are perspective views showing modified arrangements of cords for opening and closing the canopy.

Referring by numerals to the accompanying drawings which illustrate a preferred embodiment of my invention, 10 designates a post or standard, preferably, a metal pipe, the lower end of which is removably positioned in a block 11 of concrete, set in the ground.

Mounted to slide on post 10, is a short sleeve 12 carrying a set screw 13, by means of which said sleeve may be clamped to said post and pivoted at 14, to the upper end of said sleeve, is a plurality, preferably four, radial arms 15 of wood.

Strung through apertures in arms 15 in spaced parallel relation, is a cord or cable 16, from which laundered articles may be suspended while drying. The outer ends of arms 15, are provided with short horizontal slots and arranged for rotation therein are pulleys 17.

Seated on the upper end of post 10, is a flanged collar 18, to the flange of which are pivotally connected, the inner ends of wire rods 19, practically inflexible and the outer ends thereof, are pivotally secured to the outer ends of arms 15, preferably to the axes of pulleys (see Fig. 1).

When the structure is set up for use, sleeve 12 is positioned on post 10, a short distance below collar 18, so that arms 15 gradually incline toward

2

their outer ends and rods 19 gradually decline toward their outer ends.

Mounted on collar 18, is a sectional frame 20, in which are journaled four pairs of pulleys 21, arranged as shown in Fig. 3.

A canopy or cover 22 overlies the frame work comprising rails 15 and rods 19 and secured to the underside of said canopy, are radially disposed rows of rings 23, through each row of which 10 passes one of the rods 19.

The outer ends of the members of a pair of cords 24, are connected to the outer ring of each set, one cord of each pair passing around the corresponding pulley 17, with both cords extending 15 inwardly and passing over a pair of the pulleys 21 and thence downward alongside post 10.

By pulling downward on the depending portions of those cords 24 which pass around pulleys 21 the outer rings 23 of each set are drawn outwardly on

20 rods 19, thereby spreading the canopy over the frame work of the structure and when the other four cords are pulled, the outer four rings will be drawn inward on rods 19, thus folding the canopy into compacted form above flanged collar 18 and the central portion of the framework.

In Figs. 4 and 5 I have shown a modified arrangement whereby the four cords 24 which are pulled to fold or compact the canopy pass over four pulleys 25, arranged on one side of collar 30 18, with the lower ends of said cords connected to a single depending pull cord 26 and the other four cords used in opening the canopy, pass over a second set of four pulleys 27 and are connected to a single depending pull cord 28.

35 By withdrawing post 10 from block 11 and moving sleeve 12 downward on said post, the entire structure may be collapsed and compactly folded, so as to occupy comparatively little space while in storage, or during transportation.

40 The canopy 22 may be lowered over the framework and lines 16, when fabric articles that tend to fade when exposed to sunlight are being dried. The canopy, when opened over the framework, provides a shaded area of considerable size on the 45 lawn.

45 Thus it will be seen that I have provided a combined clothes drier and canopy that is simple in structure, inexpensive of manufacture and very effective in performing the functions for which it is intended.

50 It will be understood that minor changes in the size, form and construction of the various parts of my improved clothes drier and canopy, may be made and substituted for those herein shown and 55 described, without departing from the spirit of

3
the invention, the scope of which is set forth in
the appended claim.

I claim as my invention:

In a combined clothes drier and canopy, a post, a collar secured to the upper end of the post, a sleeve arranged for sliding movement on the post below said collar, means for clamping said sleeve to said post in differently adjusted positions, radial arms pivoted at their inner ends to said sleeve the outer end of each arm being provided with a vertical slot, pulleys journaled in the slots in said arms, radial rods having their inner ends pivotally connected to said collar with their outer ends pivoted to the outer ends of said arms which rods are in the same vertical plane with said arms, a plurality of rings forming a set arranged for sliding movement on each rod, a frame on said collar, pulleys mounted for rotation on said frame, cords passing over said last mentioned pulleys and

5
around the pulleys in the outer ends of said arms, said cords being connected to the outer ring of each set and a canopy covering said rods and arms and connected to said rings.
